US00D678842S

(12) **United States Design Patent**
Shino et al.

(10) **Patent No.:** US D678,842 S
(45) **Date of Patent:** ** Mar. 26, 2013

(54) **CONNECTOR FOR ELECTRONIC EQUIPMENT**

(75) Inventors: **Yoshihiko Shino**, Kawasaki (JP); **Takafumi Nishida**, Kyoto (JP); **Daisuke Kumazaki**, Kyoto (JP); **Yuji Hori**, Kyoto (JP); **Junji Takamoto**, Kyoto (JP)

(73) Assignee: **Nintendo Co., Ltd.**, Osaka (JP)

(**) Term: **14 Years**

(21) Appl. No.: **29/407,695**

(22) Filed: **Dec. 1, 2011**

(30) **Foreign Application Priority Data**

Jun. 3, 2011 (JP) 2011-012659
